CLAUS H. LIGHT, OF DES MOINES, IOWA, ASSIGNOR OF ONE-HALF TO EDWIN RUDNICH,
OF MANNING, IOWA.

ELECTRIC SIGNAL.

1,157,990.

Specification of Letters Patent.

Patented Oct. 26, 1915.

Application filed March 17, 1913. Serial No. 755,027.

To all whom it may concern:

Be it known that I, CLAUS H. LIGHT, a citizen of the United States, residing at Des Moines, in the county of Polk and State of Iowa, have invented a certain new and useful Electric Signal, of which the following is a specification.

The object of my invention is to provide an electric signal designed especially for use 10 in connection with fire hose and the like provided with current carrying wires countersunk in the walls of the hose and couplers comprising the fire hose and arranged so that the hose sections may be detached 15 without attention to the wires, said wires being arranged so that they may be connected with a battery at the union of any one of the couplers to carry a current therefrom to a signal light, bell or buzzer at any suitable place on the hose or nozzle, said signal 20 being arranged to be operated by means of a key or switch placed at a point distant therefrom.

A further object is to provide a simple 25 and effective means contained within the walls of the couplers for detachably connecting the ends of the wires in the adjacent hose and also to provide means whereby a battery may be connected with the wires countersunk in the hose at any union of the adjacent sections of said hose.

My invention consists in certain details, in the construction, arrangement and combination of the various parts of the device, 35 whereby the objects contemplated are attained, as hereinafter more fully set forth, pointed out in my claim and illustrated in the accompanying drawings, in which:

Figure 1 shows a sectional view of a fire 40 hose provided with my electric signal, said signal being shown in diagram thereon. Fig. 2 shows a circumferential, sectional view taken through the middle of adjacent couplers, and Fig. 3 shows a longitudinal, 45 sectional view taken on the line 3-3 of Fig. 2.

In connection with my signal device, it is necessary to employ a form of coupler for the hose that will always insure a constancy 50 of the circumferential positions of the adjacent sections of the coupler so that the contact points on the ends of the sections will at all times engage each other. For this purpose, I employ the form of coupler embodied in an application filed by me and ac-

companying the present application, Serial Number 755,026, filed March 17, 1913. This coupler comprises two telescopically connected sections 10 and 11 held in closed position by means of spring actuated loops or 60 clamps.

Referring more in detail to the drawings, I have used the reference numeral 12 to indicate the sections of a hose fitted at their ends to the coupling devices 10 and 11. 65

13 represents a nozzle or play pipe fitted to the end of the hose.

In the present form of my device, I have shown mounted on the nozzle a lamp 14 and a buzzer 15. Both of these are used as signal devices and are electrically connected with batteries by means of insulated wires embedded in the walls of the hose and couplers. 70

16 represents the wires in the lamp circuit 75 connected with a battery 17 and operated by a switch 18.

19 represents the wires in the buzzer circuit connected with a battery 20 and operated by a ringing key 21. 80

Obviously, it is essential that the electric wires be arranged in such a manner that the hose sections can be quickly detached without manually disconnecting the wires, and therefore I have employed in each of the 85 couplers the following arrangement for securing a contact of the wires in adjacent hose sections. A bore is provided in the walls of each portion of the couplers and into it is fitted an insulated tube 22 provided with a flange 23. The wire entering this tube is provided with a metal disk 24 fitted in the inner end of the insulated tube. Resting against the metal disk within the tube is a coil spring 25 and a metal contact 90

plug 26 is inserted in said tube in position against the spring with its rounded end projecting a slight distance beyond the wall of the coupler section. A lug 27 is fixed to the contact plug and operates within a slot in 100 the insulated tube to limit the outward movement of said plug. I have provided a gasket 27a between the inner adjacent edges of the coupling devices to form a water tight joint to prevent water within the hose from 105 coming in contact with the electric contact devices and thereby short-circuit the current therein.

For connecting a battery with the electric wires, the following device is provided. At 110

the union of two sections of the hose where the ends of the contact plugs are projected parallel metal strips 28 are fitted over the ends of the contact plugs and extended outwardly beyond the periphery of the hose coupler where they are connected to wires leading to the battery. Insulated cross pieces 29 are employed between the parallel strips.

10 In the construction of my device, the signals consist of a lamp, bell or buzzer and may be attached to the hose at any suitable point thereon. The wires running from the signals to the batteries are preferably built in the walls of the hose or embedded in grooves therein. Each battery and its key or switch for controlling it are preferably placed together within a box with wires connected thereto and carrying at their ends 15 the parallel arms for connecting the batteries with the wiring on the hose at any one of the sectional joints.

Among the advantages to be derived from the use of my device may be mentioned the following: Where a fire is burning in a remote part of a building and a considerable length of hose has been extended inside thereof, it is of course difficult for the firemen at the nozzle of the hose to observe 25 the danger of their surroundings. Where the nozzle is provided with signals, as shown herein, any person on the exterior of the building noting an impending crash of the walls or roof can, by operating the switch or key, quickly warn the firemen within the 30 building of their immediate danger.

Another advantage in the use of my signal device is to be found in cases where fire is confined to a smoke filled room, in which 35 case, if the nozzle is provided with a key

or switch and the signal device is located on the hose at a point a considerable distance from the nozzle, the firemen feeling themselves overcome by the effects of the smoke, can, by operating the switch or key, signal 45 to persons stationed outside of the building for help.

I claim as my invention:

In a device of the class described, the combination of detachable hose sections, an electrically operated device mounted on said hose, conducting wires extending along said hose and connected at one end to said device, a sleeve mounted in each section adjacent to the end of the section, contact points slidably mounted in said sleeves, means for limiting the movement of said contact points, yielding devices tending to hold said contact points projecting slightly beyond the ends of the sections in which they are mounted, 60 means for electrically connecting the contact point with the wires, a source of electric power, wires connected therewith, a switch operatively connected with one of said wires, means for connecting said last described 65 wires with said contact points, said means comprising a pair of parallel arms adapted to have their ends inserted into the space between two adjacent sections with said ends fitted over said contact points, which contact points are held projected into said arms by said yielding means, insulator bars connecting said parallel arms, and means for connecting the upper ends of said wires connected with said battery. 70 75

Des Moines, Iowa, March 8, 1913.
